UNITED STATES PATENT OFFICE

HERMAN R. FREUND, OF BROOKLYN, NEW YORK, ASSIGNOR TO INTERTYPE CORPORATION, OF BROOKLYN, NEW YORK, A CORPORATION OF NEW YORK

MATRIX-COMPOSING STICK

Application filed November 13, 1928. Serial No. 319,085.

The present invention relates to improvements in typographical machines and more particularly to those of the class shown and described in Letters Patent No. 436,532 granted September 16, 1890, to O. Mergenthaler wherein matrices bearing type forming characters and spacers are released from their places of storage in the machine by the operation of a keyboard and are automatically assembled in lines, and each line is transferred automatically during the operation of the machine into a so-called "first elevator" which lowers the line to the casting position in front of a mold in which a type bar or slug is cast against the characters of the matrices in the line, the line of matrices and spacers being subsequently removed from said elevator and the matrices and spacers returned to their places of storage automatically by the appropriate mechanisms usual in machines of this class.

In composing lines for ordinary printed matter, the supply of matrices usually contained in the machine, especially when the machine contains a plurality of matrix magazines, is sufficient to meet the demands as to sizes and styles of type for such printed matter, but some classes of printed matter, especially advertising matter, call for headings or lines made up of artistic, display or other odd or distinctive characters to contrast with the body of the printed matter, and while line casting machines of this class as now constructed usually provide for the automatic assembling of matrices having odd or unusual characters, it is impracticable to carry in the machine the great variety of matrices that would be required to meet all demands.

It has been proposed to meet these requirements by providing a special machine employing special matrices for the casting of unusual type faces or characters, but the use of a special machine for the purpose is objectionable as it imposes upon the print shop the expense of such a machine for casting the unusual or special lines of type in addition to a line casting machine of the usual class for casting the usual or ordinary lines of type. It has also been the practice, to some extent, for print shops to compose the special or unusual

lines from ordinary foundry type, such lines to be assembled in the printing frame with the usual type slugs cast in the ordinary line casting machine, but after such mixed type have served their purpose, it is necessary to separate the foundry type from the lead type slugs which were cast in the line casting machine, in order that the lead slugs may be returned to the metal pot of the machine and the foundry type distributed to their proper receptacles in the type cases, and as this work was necessarily performed by hand, it was slow, laborious and expensive. Moreover, foundry type wears, due to repeated use thereof in printing, and hence there is no certainty that the type faces thereof will be at the proper full height occupied by the type faces of type slugs freshly cast in the molds of line casting machines against matrices which are positioned so accurately in such machines as to always insure the production of slugs the type faces of which are at the full and proper height. Consequently, if ordinary foundry type are mixed with type slugs cast in the usual line casting machines, lack of uniformity in the impression made therefrom will result.

The primary object of the present invention is to provide novel means whereby matrices of the usual standard form used in the usual line casting machines but bearing special or odd designs of type forming characters and stored outside of the machine, may be composed by hand, either with or without spacers, on a matrix composing stick or member, and the latter may be fitted or applied to the usual "first elevator" of the ordinary line casting machine in such a manner that it will align the matrix line thereon with the matrix channel in said elevator, to which the matrix line may be transferred from said stick or member into the first elevator and said stick or member removed from the latter, the first elevator then operating in its usual way to convey the matrix line to the usual casting position in front of the mold in the machine so that a cast may be made therefrom in the usual way during the usual automatic operation of the machine. After the cast has been made from the matrix line, it

may be either returned to the stick or member on which it was composed, by re-applying said stick or member to the first elevator and transferring the matrices or the matrices and spacers thereto, and the matrices may be removed from the stick or member and distributed by hand to the type case or cases from which they were drawn, or in certain instances, the matrix line may be left in the first elevator after the cast has been made therefrom so that the matrices composing the line may be separated from the spacers and carried through the usual distributing mechanism of the machine and eventually brought into the usual pi stacker from which they may be removed at leisure and the spacers, if such were used in the line and separated from the matrices, will be automatically conveyed to the usual magazine therefor contained in the machine, by the operation of the usual mechanisms of the machine.

To these and other ends, the invention consists in certain improvements as will be hereinafter more fully described, the features of novelty being pointed out particularly in the claims at the end of the specification.

In the accompanying drawings:—

Fig. 1 is a front elevation, partly broken away, of a portion of the first elevator of a line casting machine of the class hereinbefore referred to, showing a matrix composing stick or member embodying the present invention applied thereto and indicating by the full and dotted lines the manner in which a matrix line is transferred from the composing stick or member to the first elevator;

Fig. 2 represents a top plan of a portion of the structure shown in Fig. 1;

Fig. 3 represents a transverse section through a portion of the first elevator and the composing stick or member, taken on the line 3—3 of Fig. 1 and looking in the direction of the arrow;

Fig. 4 represents a transverse section taken through the first elevator on the line 4—4 of Fig. 1 and looking in the direction of the arrow, the matrix line including spacers being shown in position in the first elevator in full lines;

Fig. 5 is a perspective view of the cooperating portions of the first elevator and the matrix composing stick or member, illustrating the manner in which the latter may be applied to and detached from the first elevator;

Fig. 6 is a view similar to Fig. 1 but showing another embodiment of the matrix composing stick or member applied to the first elevator of a line casting machine;

Fig. 7 is a top plan view of the structure shown in Fig. 6, with a portion thereof broken away;

Fig. 8 represents a transverse section through the matrix composing stick or member and the matrix line thereon, the section

being taken on the line 8—8 of Fig. 6 and looking in the direction of the arrow;

Fig. 9 represents a section taken transversely through the matrix composing stick or member and the matrix line thereon, the section being taken on the line 9—9 of Fig. 6 and looking in the direction of the arrow;

Fig. 10 represents a transverse section through a matrix composing stick like that shown in Figs. 1 to 5 inclusive, but modified to show different means for supporting the matrices thereon.

Similar parts are designated by the same reference characters in the several figures.

The present invention is applicable generally to line casting machines which employ a channelled member, such as the first elevator of machines of the class hereinbefore referred to, which receives a matrix line, composed of matrices alone or matrices and spacers, and conveys the matrix line to casting position where a type bar or slug is cast against the type forming characters in the matrices. The preferred embodiments of the invention are shown in the accompanying drawings and will be hereinafter described in detail, but it is to be understood that the invention is not restricted to the precise construction shown since equivalent constructions may be used and such are included within the scope of the claims.

The invention is shown herein as adapted for use in connection with a line casting machine of the class shown and described in the Mergenthaler patent hereinbefore referred to, 1 representing the head of the so-called first elevator which receives the matrix lines and lowers them to casting position in front of a mold, and 2 and 3 representing the jaws of the first elevator which are spaced apart and form a channel in which the matrix line is received, these jaws being usually formed with oppositely located ledges or rails 4 on which the upper lugs or ears *m* of the matrices are adapted to rest whereby the matrices are supported in the elevator, and the elevator jaws being also usually formed with oppositely located ledges or rails 5 located above the matrix supporting rails 4 on which the out-turned ears *s* on the upper ends of the usual spacers *S* are adapted to rest and by which the spacers are supported in the elevator. It is also usual to form the jaws of the first elevator with opposed longitudinal recesses 6 located above the spacer supporting rails 5 to permit matrices to be supported in high alignment in the elevator, as when the forward lower lugs or feet *m'* of the matrices rest on the rail 7. The first elevator usually embodies a slide which is movable vertically in a so-called vise frame, this vise frame being pivoted toward its lower end so that it may be swung forwardly out of its normal operative position into a posi-

110
115
120
125
130

tion where the right hand or matrix receiving end of the elevator is exposed and accessible, such mounting of the first elevator on the pivoted vise frame being shown and described in the Mergenthaler patent referred to.

The present invention provides a matrix composing stick or member which is normally separate from the machine and may be handled manually, either by the operator of the machine or by a compositor for the assembling or composing of a matrix line thereon from matrices the form and construction of which conforms with the standard matrices commonly used in line casting machines of this class but which bear type forming letters or characters which are of an artistic, display or odd kind such as would not ordinarily be contained in the machine but might 10 be contained in a cabinet or case and would be suitable for the composition of lines to serve as headings or the like in printed matter, these odd character matrices being selected and composed by hand on the composing bar or member, either with or without depending expansible spacers like or similar to those generally used in line casting machines of the class referred to, so that they are suspended and hang from its other side. The 15 composing stick or member is so constructed that it may be readily attached or applied to the matrix receiving end of the first elevator of the machine, after the vise frame has been released and swung forwardly, and when the 20 composing stick or member is so applied to the first elevator, it will aline the supporting means on the matrices or matrices and spacers constituting the line with the corresponding supporting means in the first elevator, and the matrix line may be transferred 25 from the composing stick by simply sliding the line by hand in a direction from the composing bar toward the first elevator. After the vise frame has been restored to its normal 30 position and the machine has been started into operation, the line thus introduced into the first elevator is lowered to the casting level and justified in the usual manner while occupying a position in front of the slug casting mold, a slug is cast in the mold against the character faces of the matrix line, and the continued operation of the machine automatically raises the first elevator and thus 35 removes the matrix line from casting position. The matrix line may be permitted to remain in the first elevator, in which case the continued operation of the machine will automatically separate the matrices from the spacers, if spacers were used in the line and 40 will pass the matrices through the distributing mechanism of the machine and bring the odd matrices which compose the line into the usual pi-stacker of the machine, from which they may be removed at any time, while the continued operation of the machine will auto- 45

matically return the spacers, if any, to the usual space box, as takes place in the ordinary operation of a machine of this class, or, after a cast has been made from the matrix line containing special odd character matrices, the 50 vise frame of the machine may be released and swung forwardly, the composing stick on which the matrix line was composed or one similar to it, may be fitted or applied to the right hand or matrix receiving end of the 55 first elevator, and the matrix line may be transferred from the first elevator to the composing stick by sliding the line by hand in the appropriate direction, after which the composing stick which will then contain the 60 matrix line may be detached from the first elevator, and the line disassembled and the matrices distributed to the places in the case or cabinet from which they were drawn.

In the embodiment of the invention shown 65 in Figures 1 to 5 inclusive, the composing stick or member comprises a bar 8 which is substantially V-form in cross section to conform with the V-shaped recess commonly used in the standard matrices employed in line 70 casting machines, and the sides of this bar are formed with longitudinal teeth which conform with and are adapted to receive the teeth m^2 commonly formed in the two sides of the V-shaped recess in the top thereof. Each matrix to be used on the composing stick may be engaged on the bar 8 by inserting it at the end of the bar 8 in such a manner 75 that the teeth m^2 of the matrix engage between the proper teeth on the bar 8, the right hand or matrix receiving end of the toothed bar 8 or the teeth thereon, being preferably bevelled or tapered as at 8^a to facilitate the insertion of the matrices thereon. When the matrices are assembled on the bar 8, they will be supported or suspended thereon by the teeth m^2 of the matrices which interengage the teeth on the bar so that they hang from the under side of the stick, it being understood that the 80 matrices are applied to the composing stick 85 in the order in which they are to be presented in the matrix line. The composing stick, in this form of the invention, is adapted to receive the usual standard spacers which may be inserted at the appropriate places in the 90 matrix line during its composition, and for this purpose, a channelled plate 9 is provided above the matrix supporting bar 8, this plate 9 being channelled at its opposite edges to form rails 10 to receive the outturned supporting lugs s which are provided at the upper ends of spacers of the standard type used in line casting means of this class and thereby suspend the spacers so that they hang from the under side of the stick. The channels of the plate 9 are open at the right hand or spacer receiving end in Fig. 1 so that the lugs s on the spacers may be readily inserted into the channels, the spacers being usually formed 95 with an untoothed notch or recess s' in its up- 100

per edge which will clear the toothed matrix supporting bar 8. The spacer supporting plate 9 is located at such an elevation with respect to the matrix supporting bar 8 that the composing stick will support the matrices and the spacers at levels corresponding with the levels of the matrix supporting rails 4 and the spacer supporting rails 5 in the first elevator, the bar 8 and plate 9 being shown so spaced by the interposed spacing strip 11 and the bar 8 and plate 9 being secured together by a suitable number of screws 12. The outer forward face of the plate 9 is preferably provided with a scale 13, preferably graduated in ems and half ems to assist the compositor in determining the number of matrices that can be composed into each line on the composing stick.

The composing stick is provided with means for removably attaching it to the first elevator in a manner which will aline the lower edges of the upper lugs *m* of matrices thereon with the matrix supporting rails 4 of the first elevator and will aline the lower edges of the supporting lugs *s* of the spacers supported thereon with the rails 5 of the first elevator, such means, in the form of the invention shown in Figures 1 to 5 inclusive, comprising a plate 14 which may be secured to the top of the plate 9 and is of such a width that its edges 15 are adapted to slide longitudinally into the high alinement recesses 6 in the walls of the matrix channel formed between the elevator jaws, the edges 15 of the plate thus serving to limit the height at which the composing stick is placed in the first elevator and to register the supporting lugs of the matrices and spacers transversely with respect to their supporting rails in the first elevator, and the composing stick is also provided, in this form of the invention, with a holder 16 which may be made up of sheet metal bent into channel form so that its sides will enter the channel or space between the elevator jaws 2 and 3, the upper edges of the sides of this holder being turned outwardly to form flanges or rails 17 which will overlie and rest on the tops of the elevator jaws, substantially as shown in Figure 3. The opposite sides of the holder 16 may be rigidly secured in proper spaced relation by rivets 18 extending therethrough and having spacing sleeves 19 fitted thereover and filling the space between the sides of the holder. The holder may be secured rigidly to the plate 14 by a suitable number of rivets 18^a as shown in Figure 3. The extent to which the composing stick is inserted into the matrix receiving end of the first elevator is limited by suitable stops or shoulders. Preferably these stops are formed by the end 20 of the channelled plate 9 which terminates short of the end of the holder 16 so that the latter may be inserted into the space between the elevator jaws for a distance sufficient to support

the composing stick when the end 20 of the plate 9 abuts against the adjacent end wall of the elevator.

When a composing stick as shown in Figures 1 to 5 inclusive is thus applied to the matrix receiving end of the matrix channel of the first elevator, the toothed bar 8 will support the matrices at such a level that the lower edges of the upper supporting lugs *m* of the matrices will be level and alined with the matrix supporting rails 4 in the elevator and the rails 10 will support the spacers at such a level that the supporting lugs *s* of the spacers contained in the composing stick will be level and alined with the spacer supporting rails 5 in the elevator, and the matrix line, together with any spacers therein, may be easily and quickly transferred from the composing stick to the first elevator by simply sliding the matrix line in a direction from the composing stick toward the first elevator or in a direction from the right toward the left in Figure 1, the matrix line being thus shifted from the full line position to the dotted line position in that figure, catching of the matrices or spacers upon the respective supporting rails in the first elevator being avoided, due to the alinement of the supporting lugs of the matrices and spacers on the composing stick with the respective supporting rails in the first elevator. After the line has been thus transferred from the composing stick to the first elevator, the empty composing stick may be removed by simply withdrawing it endwise from the first elevator or by moving it toward the right in Fig. 1, and after the vise frame has been returned to its normal position, the machine may be started and it will operate as with ordinary matrices, to cast a type bar or slug against the matrix line introduced into the machine from the composing stick, as just described. After the cast has been made, the line may be permitted to pass through the machine in the manner hereinbefore described, or the line may be removed directly from the first elevator by replacing the composing stick on the first elevator, after the latter has been swung forwardly and then shifting the matrix line by hand from the dotted line position to or toward the full line position in Fig. 1, the supporting teeth and lugs of the matrices and spacers respectively, contained in the first elevator, alining with the toothed bar 8 and rails 10 respectively on the composing stick, so that the matrices and spacers may be returned to the composing stick without catching of the matrices or spacers on the toothed bar 8 or rails 10, the toothed bar 8 or the ends of the teeth thereon, being preferably bevelled as at 8^b to facilitate the re-engagement of the teeth of the matrices therewith, and after the matrix line has been received by the composing stick, the latter may be detached from the first elevator, by simply withdraw-

ing it endwise toward the right in Fig. 1 so as to disengage its holder 18 and the edges 15 of the plate 14 from the first elevator, and the matrices and spacers may be disassembled 5 from the composing stick by hand, by sliding them endwise upon the bar 8 and rails 9, and the matrices and spacers may then be returned to their proper places in the cabinet or case from which they were drawn. In this 10 form of the invention, the holder 16 will serve not only to mount, aline and support the composing bar with respect to the first elevator but it also may serve as a handle which may be grasped by the left hand of the compositor 15 and thus provide means for holding the composing bar while the matrix line is being assembled thereon.

In the embodiment of the invention shown in Figs. 6 to 9 inclusive, a toothed bar 80 is 20 employed for supporting or suspending the usual standard form of matrices by engagement with the teeth thereof so that they hang from the under side of the stick, this toothed bar corresponding with the toothed bar 8 in 25 the construction hereinbefore described, but this toothed bar 80, in this form of the invention, serves also to support or suspend spacers S', the bodies S² of which are formed with V-shaped notches in their upper edges and 30 with teeth S³ which conform with the teeth on the bar 80 so that the teeth of these spacers will interengage the teeth on the bar 80 and such spacers as well as matrices having similar teeth on their upper edges, may be supported by the toothed bar 80. In using spacers of the constructions just described, the upper supporting lugs s employed on the spacers shown in Figs. 3 and 4 are omitted, and instead, the bodies S² of the spacers are 35 formed with relatively lower supporting lugs S⁴ which are located on the same level with the upper supporting lugs m of the matrices, as shown in Fig. 9, so that the supporting lugs S⁴ of the spacers as well as the upper supporting lugs m of the matrices will be adapted to 40 be supported on the same rails 4 in the first elevator. In the embodiment of the invention shown in Figs. 6 to 9 inclusive, the matrix and spacer supporting bar 80 is secured, 45 by screws as shown, or otherwise, to a plate 81 the left hand end of which, as shown in Figs. 6 and 7, is reduced to a width which will enable this plate to enter the grooves formed in the opposite walls of the matrix channel of 50 the first elevator immediately above the usual spacer supporting rails 5, while the remainder or right hand portion of the plate 81 is made somewhat wider so that it will form a shoulder or stop 82 which is adapted to come 55 against the right hand end of the first elevator, as shown in Fig. 7, and thereby limit the extent of insertion of the composing bar into the first elevator. The matrix and spacer supporting bar 80 occupies such a height relatively to the plate 81 that when the plate 81 60

is inserted into the first elevator and rests on the rails 5 therein, the matrices M and also the spacers S² supported on the composing stick by the bar 80 thereof will occupy such a position that the lower edges of their supporting ears or lugs m and S⁴ respectively will be level and alined with the rails 4 in the first elevator, and hence the matrix line, including the matrices and spacers may be transferred from the composing stick to the first elevator by simply pushing the line endwise and toward the left in Fig. 6 by hand, the matrices and spacers being thereby transferred from the toothed bar 80 of the composing stick to the supporting rails 4 in the first elevator, these rails 4 then serving to support the matrices and spacers at the proper elevation in the first elevator. The cast is made from the matrix line in the same manner as that described hereinbefore, and since, in this 70 embodiment the matrix line must be removed from the first elevator and returned to the composing stick, due to the use of the special form of spacers which will not distribute in the usual line casting machine, the composing stick is reapplied to the first elevator by inserting its reduced end into the channels or grooves formed above the rails 5 and then sliding the matrix line by hand from the left 75 toward the right whereby the teeth in the notches in the upper ends of the matrices and spacers become engaged upon the toothed bar 80, and the composing stick with the matrix line thereon may be removed by simply withdrawing the reduced end of the plate 81 there- 80 of endwise from the first elevator. The matrices and spacers contained on the composing stick may be removed by sliding them endwise on the bar 80, and they may be returned to 85 their proper places in the cabinet or case from which they were withdrawn. In order to facilitate the stringing of the matrices and spacers on the toothed bar 80, the opposite ends of this bar, or the ends of the teeth thereon, are 90 preferably bevelled as at 80^a and 80^b, the bevelled end 80^b facilitating the placing of the matrices and spacers on the bar 80 during the 95 composing of the matrix line and the bevelled end 80^a facilitating the engagement of the teeth of the matrices and spacers on the bar 100 105 110 115 120 125 130 135 140 145 150 155 160 165 170 175 180 185 190 195 200 205 210 215 220 225 230 235 240 245 250 255 260 265 270 275 280 285 290 295 shown in Fig. 10. In this embodiment of the invention, a channelled plate 90 is employed which embodies upper channels which form rails 10^a to receive the supporting lugs *s* of the usual standard spacers, and lower channels which form rails 91 to receive the upper supporting lugs or ears *m* of the matrices, the notch *m*^a in the upper edge of the matrix being without the usual supporting teeth, so that the matrices and spacers are suspended and hang from the under side of the stick. The rails 10^a and 91 are located at such levels that they will support the lugs *s* of the usual spacers and the upper lugs *m* of the matrices to aline with and ride on to or off the rails 5 and 4 respectively in the elevator, it being understood that the composing stick may be provided with means similar to that shown in Figs. 1 to 5 inclusive, for attaching and 10 positioning the composing stick in the first elevator, and that the matrix line may be composed on the composing stick and introduced into and removed from the first elevator as described in connection with those 15 figures.

The present invention, in each of the embodiments thereof shown, enables line casting machines of the usual or well known forms to be used for the composition of as 20 much of any advertising or other matter as may be possible, omitting special artistic or display lines which call for matrices with special type faces and which are not contained in the machine, and these special lines 25 may be composed by hand, either by the operator of the machine or by a hand compositor, either along with the composition of the part of the matter composed on the machine or after the composition of that 30 matter has been completed, the matrices used in the composition of the special lines being the same in form and construction, as matrices commonly used in the machine, except that they are provided with artistic, 35 display or other odd type forming characters and they may be stored in and withdrawn as needed from an ordinary printer's type case or any other suitable cabinet or receptacle which is preferably located conveniently to the line casting machine.

The matrices, and also spacers when such are used, are simply strung onto the composing stick in the order in which they are to appear in the printed matter, by movement 55 of the matrices or the matrices and spacers endwise on the composing stick, and accidental dropping thereof from the composing stick is prevented by the bar or rails on the composing stick which support the matrices and spacers thereon and which permit removal thereof only by movement of the matrices or matrices and spacers off an end of the stick. The line-measure scale on each 60 composing stick will assist the compositor

in determining the number of matrices that can be used in each line.

Any number of composing sticks may be used according to the demands, and each composing stick will have a special matrix line composed thereon, and when a type bar or slug is to be cast from any of these matrix lines, it is only necessary for the operator of the usual line casting machine to unlock and swing forwardly the usual vise frame, thereby exposing the right hand or matrix receiving end of the usual first elevator, to slide the end of the composing stick which is toward the beginning of the composed matrix line therein, into the channel or space between the jaws of the first elevator, whereby the supporting lugs of the matrices or matrices and spacers are brought into alinement or register with the supporting rails or surfaces therefor in the first elevator, and to then slide the matrix line endwise until it has been removed from the composing stick and introduced into the first elevator, after which the composing stick is withdrawn endwise and thus detached from the jaws of the first elevator and the vise frame is returned to its normal upright position and locked. Starting of the machine into operation will then cause the special matrix line thus introduced into the first elevator to be lowered thereby to the usual casting position in front of the mold, and a type bar or slug will be cast from this matrix line in the same manner in which casts are made from matrix lines composed and assembled in the usual manner in the machine from matrices delivered from the usual magazine or magazines in the machine.

After the cast has been made from such a special matrix line, the usual operation of the machine will cause the first elevator to rise, thereby removing the matrix line from the casting position, and if the standard matrices and spacers are used in composing the line, the machine may be permitted to continue its operation, in which event, the matrices of the special matrix line will be passed through the distributing mechanism of the machine like the ordinary matrices contained in the machine except that they will be distinguished therefrom and will pass through the distributor to the pi-stacker of the machine, from which they may be removed at any time. It is usually preferable however, to remove the special matrix line from the first elevator immediately after a cast has been made therefrom, and to accomplish this, it is only necessary, in each of the embodiments herein shown, to re-insert the composing stick into the first elevator as above described, thereby alining the matrix and spacer supporting means thereon with the supporting means on the matrices or matrices and spacers in the first elevator, and to slide from the matrix line endwise

in a direction to remove it from the first elevator and to place it on the composing stick so that the matrices or matrices and spacers will be again supported thereon as they were prior to their transfer to the first elevator, and the composing bar may then be withdrawn endwise and thus detached from first elevator, and the matrix line on the composing stick may be disassembled and the matrices distributed into their proper compartments of the case or cabinet from which they were drawn.

The present invention thus enables type bars or slugs for complete advertising or other matter, including the use of special matrix lines not composable from the matrices contained in the machine, to be cast in the same machine, thus avoiding errors and omissions and obviating the expense and other objections to the use of a special machine for the casting of the special lines, and moreover, the construction of the composing stick is such that it will receive and aline thereon matrices of the usual or standard construction such as those commonly used in line casting machines of the well known class referred to and these matrices, when transferred from the composing stick to the usual first elevator of the machine are properly positioned and conducted by the first elevator to the casting position and a type bar or slug may be cast therefrom in the same manner in which slugs are cast from the matrix line composed in the usual way in the machine, the necessity of using quad blocks and special matrices to be positioned thereby being thus avoided.

I claim as my invention:—

1. A matrix composing stick having means at its under side for supporting a composed line of matrices and depending spacers thereon and embodying means to cooperate with a matrix channel of a line casting machine and to aline the matrices and the depending spacers on the composing stick with said channel.

2. A matrix composing stick having means thereon at its under side for suspending a composed matrix line and embodying means to cooperate with a matrix channel of a line casting machine to support said stick in alinement therewith and to aline supporting portions on the matrices on said stick with matrix supporting means in said channel.

3. A matrix composing stick having means for suspending a composed matrix line thereon so that it hangs from the under side of the stick and embodying means shaped to enter a matrix channel of a line casting machine having matrix supporting rails therein to aline supporting portions on the matrices on said stick with the supporting rails in said channel.

4. A matrix composing stick having means at its underside for suspending a matrix

line thereon and having a portion beyond said matrix suspending means and slidably endwise into a matrix channel in a line casting machine to support said stick at a level where the matrices thereon are alined with said channel.

5. A matrix composing stick having means for supporting a matrix line thereon and having means to fit endwise into an end of the first elevator of a line casting machine and to support said stick at a level where the supporting portions of matrices thereon are alined with the matrix supporting rails in said elevator.

6. A matrix composing stick to cooperate with the first elevator of a line casting machine, said stick having means for supporting a composed line of matrices thereon and having means to slidably enter an end of the matrix channel in said elevator and to support said stick with the matrices thereon in alinement with the channel in said elevator.

7. A matrix composing stick for introducing a matrix line composed thereon into the matrix channel of the first elevator of a line casting machine, said stick embodying means for supporting a matrix line thereon and means to removably fit into an end of the first elevator channel to support said stick in position with the matrices thereon alined with said channel.

8. A matrix composing stick for introducing a matrix line into the matrix channel of the first elevator of a line casting machine, said stick having means for supporting a matrix line containing matrices and spacers and having means movable endwise into the channel of the first elevator to support said stick and to aline supporting portions of the matrices and spacers thereon with the supporting rails therefor in said channel.

9. A matrix composing stick for introducing a matrix line into the matrix channel of the first elevator of a line casting machine, said stick having a toothed bar to engage and support the matrices thereon and having a portion extending longitudinally thereof beyond the end of said bar and movable endwise into the channel of the first elevator to aline the matrices on the toothed bar of said stick with said channel.

10. A matrix composing stick for introducing a matrix line into the matrix channel of the first elevator of a line casting machine and for engaging supporting lugs on the matrices with the matrix supporting rails in said channel, said stick having a toothed bar to engage teeth in the tops of the matrices to support them and having means at an end thereof adapted to enter an end of said first elevator channel and to support said stick with the supporting lugs on the matrices thereon alined with the matrix supporting rails in said channel.

11. A matrix composing stick for the as-

sembly thereon of matrices and spacers of the kind used in line casting machines, comprising a toothed bar to engage the teeth in the upper edges of the matrices, and a channelled member having rails to engage the out-
5 turned supporting lugs on the upper ends of the spacers.

12. A matrix composing stick for the assembly thereon of matrices and spacers of the kind used in line casting machines, comprising a toothed bar to engage the teeth in the upper edges of such matrices to support them, a channelled member having rails to engage the supporting lugs of such spacers to support them, and a holder on the stick
10 15 toward one end thereof.

13. A matrix composing stick for introducing a matrix line containing matrices and spacers into the matrix channel between the jaws of the first elevator of a line casting machine and for engaging the supporting lugs on the matrices and spacers with supporting rails in said channel, said stick comprising means on which the matrices and spacers are
20 movable endwise for supporting them, and a holder on the stick movable into a position between the elevator jaws and operative to support the stick at a level where the supporting lugs on the matrices and spacers are
25 alined with the respective supporting rails in the matrix channel.
30

14. A matrix composing stick for introducing a matrix line into the matrix channel of a line casting machine and for engaging supporting lugs on matrices and spacers with supporting rails therefor in said channel, said stick embodying a toothed bar to engage teeth in the tops of the matrices and thereby support them and rails to engage the supporting lugs of spacers to support them, and means on the stick for mounting it on the first elevator at a level where the supporting lugs of the matrices and spacers are alined with the respective supporting rails in the elevator.
